CALENDAR

Filed Dec. 5, 1930

UNITED STATES PATENT OFFICE

WILLIAM DABNEY WHITE AND CHARLES WRIGHT MACMILLAN, OF PASSAIC, NEW JERSEY

CALENDAR

Application filed December 5, 1930. Serial No. 500,356.

This invention relates to calendars, and has particular reference to an improved day-by-day calendar, in which a subdivided strip having indicia designating the days of a given year, month and week is movable past the display opening.

The present invention broadly aims to provide in a calendar of the indicated character, an improved means located within the display opening, with which the designated strip subdivisions cooperate for marking out the current day, while other remaining days past and/or future are visible for ready reference.

The instant invention further aims to provide a calendar of the character set forth, which employs but few and simple parts, capable of economical production and assembly, which calendar may be operated either manually or mechanically, such as by a clock mechanism, and which serves effectually to perform the function for which it is designed.

With the above recited and other objects in view, reference is had to the following description and accompanying drawings, in which there is exhibited one example or embodiment of the invention, while the claims define the actual scope of the same.

In the drawings:

Figure 1 is a perspective view of a calendar constructed in accordance with the invention.

Figure 2 is a face view thereof on an enlarged scale, parts being broken away and shown in section to disclose the underlying structure.

Figure 3 is a longitudinal sectional view taken approximately on the line indicated at 3-3 in Figure 2.

Figure 4 is a fragmentary face view of the calendar strip.

Referring to the drawings by characters of reference, 5 designates generally a casing or housing which includes a rear or bottom wall 6 and marginal end and side walls 7 and 8, the front or top being open and, in the example shown, being provided with a frame 9 defining a display opening 10. Obviously, the casing or housing 5 may be constructed of wood, as illustrated, or of metal or any equivalent material. The casing or

housing is divided by a transverse partition 11, which extends from the bottom or rear wall 6 to a point spaced from the plane of the frame 9 and from one side wall 8 to the other, as clearly disclosed in Figures 2 and 3 of the drawings. A backing panel 12 disposed in a plane parallel to the frame 9 and slightly spaced therebehind is secured to the partition 11, extends from one side wall 8 to the opposite side wall and has its remaining rounded edges 13 spaced from the end walls 7. This construction of the casing or housing provides a pair of compartments 14 and 15, within which transversely arranged spools are mounted for rotation, access being gained to the compartments 14 and 15 by removing the screws or equivalent fastening elements 16 which secure the backing panel 12 in place.

The spools as shown each include a cylindrical shank or core 17 having reduced opposite extremities 18 and 19, the former being of greater length than the latter, to provide a manipulating extremity which protrudes beyond the casing or housing wall. The reduced extremities serve also as trunnions which bear in bearing openings 21 in the side walls 8 of the casing or housing. Disks 22 having apertures 23 of a diameter to snugly fit over the reduced extremities 18 serve as the spool flanges and may be secured thereto by a tack 24. A pair of plain washers 25 with a split lock washer 26 may be positioned over the reduced extremity 18 of each spool and interposed between the disk 22 and the inner surface of the side wall 8, while the remaining reduced terminal may have a plain washer 27 arranged thereover and interposed between the disk and the inner surface of the side wall 8.

A calendar strip 28 of a length to accommodate the weeks of one or more years is initially wound on the spool in the compartment 15 and its outer end is trained around one of the rounded edges 13, over the outer face of the backing panel 12 around the opposite rounded edge 13 and secured to the core 17 of the spool in the other compartment 14. This disposes a longitudinal portion of the entire printed width of the calendar strip

28 directly behind the frame 9 for display through the frame opening 10 and, obviously, by turning the spool in the compartment 14 in a counterclockwise direction, as shown by 5 the arrow in Figure 3, the calendar strip 28 will be wound upon said spool and unwound from the spool in the compartment 15, to feed and move the strip longitudinally past the frame opening 10. As illustrated in Figures 1 and 2, the extremity 18 of the spool in the compartment 14 projects from the right-hand side of the casing or housing, while the longer manipulating extremity 18 of the spool in the compartment 15 projects 15 from the left-hand side of the casing or housing 5, whereby both hands may be used in properly adjusting the exposed portion of the calendar strip with reference to the frame opening 10.

20 The calendar strip as shown is longitudinally subdivided by the transverse longitudinally spaced pairs of lines 30 and transversely subdivided by the longitudinal lines 31 presenting transverse rows of blocks or areas 32 representing the days of the weeks of a given year. Between each pair of subdivision lines 30, indicia 33 are inscribed, indicating the name of the day of the week, while the right-hand area has inscribed therein indicia 34 indicating the year. Within the block or area 32, indicia 35 indicate the date of the day, the remaining portion thereof affording a diary space upon which the user may write matter, such as appointments, engagements 30 or other memoranda. The right-hand block or area 32 of each row will have inscribed therein indicia 36 indicating the name of the month, the number of the month and the number of the week of a given year.

40 In order to provide means within the confines of the frame opening 10, with which the subdivisions of the strip cooperate to selectively mark out the current day, a transversely angularly disposed edge or line 37 45 is provided, which in the present instance is shown as the lower stepped edge of a bar 38 which forms a part of the frame 9 and which subdivides the frame opening so that past and future days are visible, in addition to the current day marked out.

From the foregoing, it will thus be seen that an improved calendar has been devised, by virtue of which the user may at a glance 50 determine the current day while having reference to past and future days. The user may also instantly determine the month, the number of the month and the number of the week. By adjusting the calendar strip 28 forwardly or rearwardly, days which are not simultaneously visible with the current day 55 may be referred to, as well as memoranda which may appear in the diary space allotted to said days.

While there has been illustrated and described a single and preferred embodiment 60

of the invention, it is, of course, understood that there is no intention to limit the invention thereto, but that variations and modifications which properly fall within the scope of the appended claims may be resorted to 70 when desired.

What is claimed is:

1. A calendar including a strip having longitudinally spaced subdivisions representing the weeks of a given year and having transversely spaced subdivisions representing the days of the week and a stationary element having corresponding longitudinally and transversely spaced means past which element the strip is movable longitudinally and with which strip said means cooperates to selectively mark out the current day. 75

2. A calendar including a strip having longitudinally spaced subdivisions representing the weeks of a given year and having transversely spaced subdivisions representing the days of the week and a stationary element having corresponding longitudinally and transversely spaced means past which element the strip is movable longitudinally and with which strip said means cooperates to selectively mark out the current day while displaying the days of the immediate future 85 and the near past. 90

3. A calendar including a strip having longitudinally spaced subdivisions representing the weeks of a given year and having transversely spaced subdivisions representing the days contained in said weeks, a casing having a display opening through which the entire 100 width of a portion of the length of the strip is visible and a stationary element having corresponding longitudinally and transversely spaced means past which element the strip is movable longitudinally and with which strip said means cooperates to selectively mark out the current day. 95

4. A calendar including a strip having longitudinally spaced subdivisions representing the weeks of a given year and having transversely spaced subdivisions representing the days contained in said weeks, a casing having a display opening through which the entire 110 width of a portion of the length of the strip is visible, a stationary element having corresponding longitudinally and transversely spaced means past which element the strip is movable longitudinally and with which strip said means cooperates to selectively mark out the current day and week and indicia in said 115 subdivisions setting forth respectively the name of the day, the date of the day, the year, the month, the number of the month, and the number of the week. 120

5. A calendar including a strip having longitudinally spaced subdivisions representing the weeks of a given year and having transversely spaced subdivisions representing the days of the week and a stationary element presenting a transversely angular edge, the 125 130

leading and trailing ends of which edge are spaced apart a distance equal to the spacing of the longitudinal subdivisions, and past which element the strip is movable longitudinally and with which strip said angular edge cooperates to selectively mark out the current day.

6. A calendar including a strip having longitudinal subdivisions representing the weeks of a given year and having transverse subdivisions representing the days of the week, a casing having a display opening through which the entire width of a portion of the length of the calendar is visible and means within the confines of said opening past which the strip is movable longitudinally and with which means said strip cooperates to selectively mark out the current day, said means consisting of a bar disposed transversely of the path of movement of the strip and provided with an angularly disposed edge, the longitudinal subdivisions being spaced apart a distance equal to the distance between the leading and trailing ends of the angularly disposed edge.

7. A calendar including a strip having longitudinal subdivisions representing the weeks of a given year and having transverse subdivisions representing the days of the weeks, a casing having a display opening through which the entire width of a portion of the length of the calendar is visible and means within the confines of said opening past which the strip is movable longitudinally and with which means said strip cooperates to selectively mark out the current day, said means consisting of a bar disposed transversely of the path of movement of the strip and provided with a stepped edge, the longitudinal subdivisions being spaced apart a distance equal to the distance between the leading and trailing steps of the stepped edge.
